UNITED STATES PATENT OFFICE.

MORTON C. HUTCHINSON, OF WOODBURY, NEW JERSEY, ASSIGNOR OF ONE-HALF TO
LEON G. BUCKWALTER, OF MERCHANTVILLE, NEW JERSEY.

STRIP-PULLING DEVICE FOR MACHINES FOR MAKING BOILER-RETARDERS.

1,333,254.

Specification of Letters Patent.

Patented Mar. 9, 1920.

Application filed October 7, 1918. Serial No. 257,249.

To all whom it may concern:

Be it known that I, MORTON C. HUTCHINSON, a citizen of the United States, residing at Woodbury, in the county of Gloucester, 5 State of New Jersey, have invented a new and useful Strip-Pulling Device for Machines for Making Boiler-Retarders, of which the following is a specification.

In a patent granted me on April 23rd, 10 1918, No. 1,263,896, I have shown and broadly claimed a novel construction of a machine for expeditiously manufacturing thin twisted strips of metal, or boiler retarders, which are inserted in the flues of 15 boilers for the purpose of retarding the progress of the products of combustion therethrough.

It is necessary and desirable in conjunction with machines of this character to employ suitable mechanism capable of exerting a pull upon the strips in order to pull or draw them through the retarder machine, of my patent aforesaid, and in my present invention, I have shown forms of mechanism, which are especially adapted for use 25 in connection with the machine of my patent aforesaid.

In carrying out my invention, I employ a feed screw rotatably mounted in suitable 30 bearings and actuated through suitable gearing by an electric, pneumatic or other prime motor, provision being made for transforming the high speed of the motor to the desired relatively low speed of rotation 35 of the feed screw, the latter being engaged or disengaged at will with a split nut mounted on a cross-head or carriage which latter carries a manually operated device for opening and closing said nut, said carriage having also mounted thereon a device for 40 engaging the strip to be pulled through the retarder machine, said carriage being adapted to travel away from the retarder machine and pull the strip therethrough upon the 45 proper manipulation of the manually operated lever, means being also employed, if desired, for returning the carriage toward the retarder machine, so that the operation of pulling the strips through the retarder 50 machine and returning the cross-head or carriage to engage a fresh strip, may be carried on without loss of time or labor.

To the above ends, my invention consists of a novel construction of strip pulling machine, which is capable of adaptation to

various uses, but particularly for use with boiler retarder machines of the construction aforesaid.

For the purpose of illustrating my invention, I have shown in the accompanying 60 drawings two forms thereof which are at present preferred by me, since the same will give in practice satisfactory and reliable results. It is to be understood, however, that the various instrumentalities of which 65 my invention consists can be variously arranged and organized and that my invention is not limited to the precise arrangement and organization of these instrumentalities as herein shown and described. 70

Figure 1 represents a side elevation of a strip pulling machine or device embodying my invention.

Fig. 2 represents a section on line 2—2 of Fig. 1. 75

Fig. 3 represents a plan view of another embodiment of my invention.

Fig. 4 represents a side elevation of Fig. 3.

Fig. 5 represents a section on line 5—5 of Fig. 3. 80

Similar numerals of reference indicate corresponding parts.

Referring to the drawings:—

I have shown herein two embodiments of the broad principle of my invention, the 85 construction seen in Figs. 1 and 2 being preferably employed, although the construction seen in Figs. 3, 4 and 5 will be found equally efficient, if desired.

In carrying out my invention, I will first 90 describe the construction seen in Figs. 1 and 2, wherein I employ an electric or other motor 1, on whose shaft 2 is mounted the pinion 3, which meshes with the gear 4, which is fast on the feed screw 5, one end of 95 the latter being mounted in suitable bearings 6 in the uprights 7 and 8, while the other end of said feed screw is mounted in bearings 9 in the top of the bracket or upright 10. The uprights 8 and 10 are braced by a 100 pair of longitudinally extending horizontal guide rods 11, on which is slidably mounted the carriage or cross-head 12.

As will be apparent from Figs. 1 and 2, the carriage or cross-head 12 is mounted on 105 the guide rods 11 at four points, as indicated at 13 and 14, said carriage or cross-head also carrying the guide member 15, having an opening in its upper portion, through which the screw 5 passes and which prevents said 110

screw from sagging. The carriage 12 is provided with transverse ways, as indicated at 16, within or upon which the block or jaw 17 is suitably mounted to slide transversely, said block having the rod 18 passing therethrough. The outer end of the rod 18 has a cam member 19 pinned thereto, while the opposite end of said rod has the lower portion of the manually operated lever 20 pinned thereto and provided with the cam member 21, which is actuated in unison with said rod 18 and said lever 20.

22 designates a block or jaw located oppositely to the block or jaw 17 and carrying the cam member 23, the jaw member 17 carrying the cam member 24.

25 designates a recess in the jaw 17 juxtaposed to which is the recess 26 in the jaw 22 within which recesses is contained the spring 27, as will be understood from Fig. 2, the construction being such that the tension of said spring normally retains said jaws in separated position, as indicated in Fig. 2, whereupon the threaded faces 28 and 29 thereof, which constitute a split nut, are out of engagement with the feed screw 5. The construction and arrangement of the cam members are preferably such that the cam 24 is integral with or fixed to the jaw member 17, while the cam member 23 is integral with or fixed to the jaw member 22. The cam members 21 and 19 are pinned or fast upon the rod 18, so that when the handle 20 is partially rotated, the rod 18 and the cam members 21 and 19 will rotate simultaneously therewith and will cause the threaded portions 28 and 29 which constitute a split nut to approach or engage the feed screw 5, whereupon the entire carriage 40 or crosshead 12 composed of the jaws 17 and 22, the guide member 15, and the swivel 30 carrying the chain 31 and the hook 32, will be caused to travel to the right or away from the strip twisting mechanism 33, which latter conforms to the construction shown in my patent aforesaid, wherefrom it will be apparent that the strip 34, shown in dotted lines at the left of Fig. 1, will be drawn or pulled between the pairs of rollers 35 of the retarder machine 33, seen at the left of Fig. 1.

If desired, I may provide suitable ball bearings for the swivel 30, as indicated in dotted lines at 36.

55 The operation is as follows:—

It will be understood from the foregoing, that the motor 1, its shaft 2, pinion 3, gear 4 and feed screw 5, are constantly rotating, and when the parts are in the position seen in Fig. 2, the carriage 12 and its adjuncts are stationary upon the guide rods 11. When, however, the handle 20 is manually operated so as to close the threads 28 and 29, constituting the split nut upon the feed

direction from left to right, pulling the strip 34 through the retarder machine 33. When the carriage reaches a point near the upright 8, upon the proper manipulation of the handle 20, the parts again assume the position seen in Fig. 2, the split nut becoming disengaged from the feed screw and the movement of the carriage ceases. The latter may be pulled again to the left or toward the upright 10, manually, or, if desired, a weight 56 and cord 54 passing over the pulley 55 may be employed for the purpose of returning said carriage 12.

It will be understood that the contour of the juxtaposed cam faces 21 and 24 and 23 and 19, will be such that the split nut at the top of the jaws 17 and 22 will properly engage the feed screw 5.

In the construction seen in Figs. 3, 4 and 5, substantially the same general principle as already described is employed, there being two pairs of uprights 37 and 38, and 39 and 40, upon the two latter of which a pair of horizontal stationary guide rods 41 is supported, said uprights 39 and 40 supporting the front cross-head 42, whose extremities 43 are guided upon said rods 41, it being apparent that the uprights 37 and 38 are tied together by the guide rods 44, upon which slides the rear cross-head 45, whose ends 46 are guided by said rods 44.

47 designates an electric or other motor having the shaft 48 on which is mounted the pinion 49, which meshes with the gear 50, the latter being held from lateral or horizontal movement by reason of its location between the uprights 38 and 39, as will be apparent from Figs. 3 and 4.

The gear 50 is mounted on the feed screw 51, whose ends are supported at the points 52 and 53 in the cross-heads 42 and 45 respectively, said gear 50 being feather-keyed to said feed screw 51, as will be understood from Fig. 5, so that as said gear rotates, the feed screw 51, which is in threaded engagement with the upright 39, as will be understood from Fig. 5, will be simultaneously rotated, but will be caused to travel longitudinally in the desired direction by reason of its feather-keyed connection with the gear 50, whereupon the two cross-heads 42 and 45 will travel as a unit in the desired direction. The cross-head 42 is provided with a swivel or turn buckle 30 to which is attached a chain 31 and a hook 32, substantially as described in respect to Fig. 2, 33 designating the boiler retarder machine provided with rollers 35, as already described with respect to Fig. 1, and as shown in my prior patent aforesaid, No. 1,263,896.

It will be apparent to those skilled in the art, that the operation of the motor 47 rotates the shaft 48, the pinion 49 and the gear 50, the rotation of said gear by reason of its feathered engagement with the feed screw 130

51 causing the latter to travel in the desired direction and simultaneously with it the cross-heads 42 and 45 carrying with them the chain 31 and the hook 32, whereby a strip 5 may be pulled and twisted between the rollers 35, as is evident.

The motor 47 may be reversed or stopped at the proper intervals, by any suitable device commonly employed or, if desired, I 10 may employ a suitable device for stopping the motor 47 when the hook 32 is at each end of its stroke by an automatically tripped switch, the solenoid, as 57, to be electrically connected to the motor 47, so as to apply a 15 brake, as 58, by gravity, when the circuit is broken.

I have deemed it unnecessary to show or 20 describe these features in detail, as their manner of application will be apparent to those skilled in the art.

It will now be apparent that I have devised a novel and useful construction of a strip pulling device for machine for making boiler retarders, which embodies the features 25 of advantage enumerated as desirable in the statement of the invention and the above description, and while I have shown and described, in the present instance, preferred embodiments thereof which will give in 30 practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a device of the character stated, a 40 feed screw, means for rotating said feed screw, guide rods suitably supported, a cross head located below said feed screw and slidably mounted on said guide rods, which latter pass through said cross head, a hook 45 attached thereto, and a split nut comprising threaded jaws normally open and common to said feed screw and cross head for effecting the actuation of the latter.

2. In a device of the character stated, the 50 combination of a motor, a feed screw, gearing common to said motor and feed screw, a plurality of uprights, horizontal rods supported in said uprights, a cross head slidably mounted on said rods, which latter pass 55 through said cross head, a hook secured to said cross head, and a split nut comprising threaded jaws normally open and capable of being manually closed upon said feed screw for causing said feed screw to actuate said cross head and hook to exert a pull 60 on a strip of material secured to said hook.

3. In a strip pulling machine, a feed-screw, means for rotating said feed screw, a cross head slidably supported and having 65 ways thereon, jaws transversely movable on

said ways and having their upper ends constructed to form a split nut, means for normally holding said jaws normally open and disengaged from said feed screw, and means for opening and closing said jaws to cause 70 said split nut to engage with and be disconnected from said feed screw.

4. In a strip pulling machine, a feed screw, means for rotating said feed screw, a cross head slidably supported and having 75 ways thereon, jaws transversely movable on said ways and having their upper ends constructed to form a split nut, means for holding said jaws normally open and disengaged from said feed screw, means for manually 80 opening and closing said jaws to cause said split nut to engage with and be disconnected from said feed screw, and means for automatically returning said cross head and jaws. 85

5. In a device of the character stated, a feed screw, means for rotating said feed screw, a cross head slidably supported and having transverse ways thereon, jaws transversely movable on said ways and having 90 their upper ends formed into a split nut adapted to engage said feed screw, a single spring for normally holding said jaws apart, and manually operated means for closing said jaws. 95

6. In a device of the character stated, a feed screw, means for rotating said feed screw, a cross head slidably supported and having ways thereon, jaws mounted on said ways and having their upper ends formed 100 into a split nut adapted to engage said feed screw, recesses in the juxtaposed faces of said jaws, a spring in said recesses for normally holding said jaws apart, a rod passing through said jaws and having cam faces 105 thereon, cam faces on said jaws coacting with the cam faces on said rod, and means for rotating said rod.

7. In a device of the character stated, a feed screw, a pair of uprights through which 110 said feed screw passes, a gear on said feed screw between said uprights, a motor, a shaft therefor, a pinion on said motor shaft also located between said uprights and in mesh with said gear, horizontal guide rods 115 mounted in said uprights, a cross head slidably supported on said rods, which latter pass through said cross head, a hook attached to said cross head and means common to said feed screw and cross head for effecting the actuation of the latter. 120

8. In a device of the character stated, a feed screw, means for rotating said feed screw, a cross head slidably supported below said feed screw, a split nut mounted 125 on said cross head, a single spring intermediate said jaws for holding the members of said nut normally out of engagement with said feed screw, means for manually causing said nut members to engage said feed 130

screw, and means for automatically returning said nut and cross head.

9. In a device of the character stated, a feed screw, means for rotating said feed screw, horizontal guide rods, a cross head through which said guide rods pass, a split nut comprising threaded jaws common to said feed screw and cross head for effecting the actuation of the latter, and a guide carried by said cross head through which said feed screw passes.

10. In a device of the character stated, a feed screw, means for rotating it, guide rods, a cross head mounted on the latter and located below said feed screw, a split nut comprising threaded jaws common to said feed screw and cross head for actuating the latter, and a guide carried by said cross head through which said feed screw passes.

20 11. In a device of the character stated, a feed screw, means for rotating it, guide rods, a cross head mounted on the latter, jaws on said cross head having their upper ends formed with a split nut, means for holding said jaws normally apart, cam faces on the lower portions of said jaws, a rod passing through the latter, cams on said rod coacting with said cam faces, and a handle on said rod.

25 30 12. In a device of the character stated, a feed screw, means for rotating it, guide rods, a cross head mounted on the latter, jaws on said cross head having their upper ends formed with a split nut, means for

holding said jaws normally apart, cam faces 35 on the lower portions of said jaws, a rod passing through the latter, cams on said rod coacting with said cam faces, and a handle on said rod, in combination with means for returning said cross head and jaws. 40

13. In a device of the character stated, a feed screw, means for rotating it, guide rods, a cross head mounted on the latter, jaws on said cross head having their upper ends formed with a split nut, means for 45 holding said jaws normally apart, cam faces on the lower portions of said jaws, a rod passing through the latter, cams on said rod coacting with said cam faces, and a handle on said rod, in combination with means for 50 automatically returning said cross head and jaws.

14. In a device of the character stated, a feed screw, means for rotating it, a cross head slidably supported and having transverse ways therein, jaws mounted on said ways and having their upper ends formed into a split nut adapted to engage said feed screw, a spring intermediate said jaws for normally holding them apart, a rod passing 55 through said jaws and having cam faces thereon and cam faces on said jaws coacting with the cam faces on said rod.
